UNITED STATES PATENT OFFICE.

JOHN C. WHITE, OF KANSAS CITY, MISSOURI.

SCREEN-FASTENING DEVICE.

1,236,637.

Specification of Letters Patent. Patented Aug. 14, 1917.

Application filed September 25, 1916. Serial No. 121,985.

To all whom it may concern:

Be it known that I, JOHN C. WHITE, a citizen of the United States, residing at Kansas City, in the county of Jackson, State of Missouri, have invented certain new and useful Improvements in Screen-Fastening Devices, of which the following is a full and exact specification.

The present invention relates to screen fastening devices and one of the objects is to provide a neat and simple construction of fastening for securing screen frames in position against the outer faces of the blind stops of window casings. To this end a fastening means has been devised which comprises a member adapted to be conveniently attached to the inner face of the screen frame and having a part designed to be securely engaged with the inner face of the blind stop.

It is a further object to provide a construction which will be readily adjustable to different widths of blind stop members of the window frames. It is also an object to devise a fastening means which will be not only strong and efficient for the desired purpose, but also comprise a construction of but few parts which will be easy to manipulate and inexpensive to manufacture.

With these objects in view, the invention will now be described with reference to the accompanying drawing, showing forms of construction which have been devised for embodying the improvements, after which those features and combinations deemed to be novel will be severally set forth and defined in the appended claims.

In the drawing—

Figure 1 is a sectional perspective view illustrating one form of embodiment of the fastening means;

Figs. 2 and 3 are horizontal and vertical sectional views, respectively, of the same;

Fig. 4 is an elevation of a modified form;

Figs. 5 and 6 are sections taken on the lines V—V and VI—VI, respectively, of Fig. 4;

Fig. 7 is an elevation of a still further modified form; and

Fig. 8 is a section taken on the line VIII—VIII of Fig. 7.

Referring to the drawing in detail, and more particularly to Figs. 1 to 3, these illustrate a portion of a window framework formed with the usual sash runways 2 and 4 separated by the parting stop or bead 6,

the outer wall of the outer sash runway 4 being formed by the blind stop member 8. The screen frame 10 is designed to be clamped in position against the outer face 60 of this blind stop 8, and for this purpose I have devised a fastening means to be carried by the screen frame and adapted to retain the same in said position by engaging the inner face of said blind stop 8. As 65 shown in Figs. 1 to 3, this fastening means comprises a bracket portion 12 of approximately U form, provided with a bolt 14 for securing the same to the screen frame, and having a turn button 16 swivelly mounted 70 on the inner end of the bolt, whereby the button may be swung into the runway 4 into engagement with the inner face of the blind stop 8. The inner threaded end of the bolt 14 is equipped with a nut 18 for 75 holding the parts, when adjusted, in proper clamping relation. The bracket 12 projects inward a distance substantially equal to the width of the blind stop, and its bolt opening 20, as well as the bolt opening 22 of the button 16, are slightly elongated transversely 80 so that either the bracket or the button, or both, may be adjusted to correspond to the width of the particular blind stop with which the device is being used, and the 85 bracket thus fitted snugly against the adjacent face of the blind stop and the button extended substantially across the inner face of said stop.

The particular form of the bracket is such 90 as to afford a secure mounting on the screen frame, extending transversely or across the grain of the latter. The legs of the bracket are arranged in somewhat diverging relation, for facilitating the nesting of a number 95 of the brackets together in compact form suitable for packing.

In Figs. 4 to 6 is shown a construction in which the bracket 12' is formed with a body portion of substantially the same shape 100 as the bracket 12, but is also provided with vertically extending portions 24 adapted to be secured by means of screws 26 to the screen frame 10. A short bolt 14' and nut 18' are employed for mounting the button 16 which is of the same form as in the preceding construction, the head of the bolt in this case, however, being shouldered against the inner face of the bracket.

Figs. 7 and 8 show a modification in which 110 the bracket 28 is stamped somewhat in Z form for adapting the body portion of the

- same to fit the angle between the screen frame and the blind stop, with the lip portion 28' in engagement with the inner face of the blind stop as clearly shown in Fig. 8.
- 5 In this construction the bolt 30 passes through the screen frame and through the transverse slot 32 of the bracket, whereby the bracket may be adjusted as in the first modification for slightly varying widths of 10 blind stops. A nut 34 clamps the parts in adjusted position, for holding the screen in place.

From the foregoing it will be apparent that a simple and efficient construction of 15 fastening means has been devised for carrying out the desired objects of the invention. The parts of the device may be easily applied and manipulated, and will not readily get out of order. A metallic construction 20 for all the parts is preferred, and the button 16 and nut 18' may therefore be made sufficiently thin to permit lowering of the upper sash (not shown) where there is some 25 clearance or play of said sash in the runway 4; or, the blind stop may be cut out slightly on its inner face, if desired, as at 38 (Figs. 7 and 8), and the parts so proportioned as to bring the face of the lip 28' (or the button 16, as the case may be) flush 30 with the inner face of the blind stop and entirely out of the path of the sash, and thus allow entirely free movement of the latter.

While the foregoing represents practical 35 and efficient forms of embodiment of the invention, the right is reserved to such formal changes and modifications as may fairly fall within the scope of the appended claims.

Claims:

1. The combination with a window blind 40 stop and screen frame adapted to be mounted against the outer face of said stop, of a screen fastening member carried by the inner face of said frame and comprising a portion projecting inward toward the inner 45 face of said stop and abutting against the intermediate side face of the stop, and a portion projecting at substantially right angles

to said first portion in position to engage 50 said inner face of the stop for holding said frame in place.

2. The combination with a window blind stop and screen frame adapted to be mounted against the outer face of the stop, of a fastening member carried by the inner face of said frame and projecting at substantially right angles to said frame for abutting against the intermediate side face of said stop, said member being mounted on said frame for adjustment in a direction toward and from said blind stop to accommodate 60 varying widths of blind stops, said member being provided with a portion projecting horizontally in position to engage the inner face of said stop for holding said screen frame in position.

3. The combination with a window blind stop and screen frame adapted to be mounted against the outer face of the stop, of a fastening means carried by the screen frame 70 and comprising an element projecting inward toward the inner face of said stop and abutting against the intermediate side face of the stop, and a turn-button mounted adjustably for varying widths of blind stops, 75 said button being adapted to swing into engagement with the inner face of said stop for holding said screen frame in position.

4. The combination with a window blind stop and screen frame adapted to be mounted against the outer face of the stop, of a 80 fastening device carried by said screen frame and comprising a bracket portion secured to the inner face of said frame and shoudered against the intermediate side face of said stop, said bracket portion projecting 85 toward the inner face of said stop and substantially flush with said inner face of the stop, and a turn-button swivelly mounted on said bracket portion and adjustable to different widths of blind stops, said button 90 being adapted to swing into engagement with the inner face of said stop for holding said screen frame in position.

JOHN C. WHITE.
